COMBINATION RANGE

Herbert T. Burrow, Beaver Dam, Wis., assignor to
 Maileable Iron Range Company, Beaver Dam,
 Wis., a corporation of Wisconsin

Application December 31, 1935, Serial No. 57,038

1 Claim. (Cl. 126—4)

My invention relates to improvements in combination ranges, that is in coal-wood-gas ranges, or coal-wood-electric ranges, although certain features of the improvements are applicable to ranges of other types.

Heretofore, the conventional kitchen heater type of range has been equipped with a rectangular fire box section at one side of the oven (usually the left side) and a cooking top with two cooking lids therein, in addition to the gas or electric heating units above the oven section.

One object of the present invention is to provide a larger cooking top above the coal or wood burning section than is available in the conventional kitchen heater.

Another object is to provide, in a combination range, a cooking top having four coal-wood cooking plates, balanced by an equal number of gas or electric burners.

20 An additional object is to improve the efficiency of the range as a room heater, by providing an intermediate chamber between the fire box section and the oven, thus making both sides of said fire box available for the effective radiation 25 of heat, said chamber having openings in its walls whereby air may circulate through said chamber and convey heat to the room.

Another object is to provide a combination range of this type in which the rear flue is located behind the intermediate chamber instead of behind the fire box section, whereby the rear end of the latter is free to radiate heat into the room.

A further object is to provide, in a combination range of this type, a circuitous path for the products of combustion immediately below the coal-wood cooking top whereby all of the cooking lids are amply heated.

Another object is to provide an improved flue 40 at the rear of the range having a double duty shield as part thereof.

Another object is to provide a range of this type having a water tank within the intermediate or warming compartment between the fire box 45 and the oven.

An additional object is to provide, in a range of this type, a pair of doors on one side thereof to conceal the front of the fire box section and of the warming compartment (or water reservoir 50 therein) said doors being of a size and design to substantially balance the oven door on the other side of said range.

In the accompanying drawings I have illustrated one embodiment of the invention and several 55 modifications of certain features thereof:

Fig. 1 is a perspective view of a range with parts removed;

Fig. 2 is a perspective view of the coal-wood cooking top;

Fig. 3 is a rear elevation;

Fig. 4 is an elevation of a detail;

Fig. 5 is a section on the line 5—5 of Fig. 1;

Fig. 6 is a section on the line 6—6 of Fig. 3;

Fig. 7 is a front elevation of a water reservoir.

In its commercial embodiment the range comprises a suitable base 10 and a front which includes the wall 11, doors 12, 13, oven door 14 and panel 15 above the latter. The top frame casting 16 for the left hand half of the range supports the usual apertured plates 17 and 18, each having a pair of openings therein which receive the usual stove lids 19, 19, and 20, 20.

The right hand top plate 21 of the range has openings therein which in number and arrangement balance the openings for the stove lids in the left hand side, thus providing a pleasing arrangement. These openings, which are indicated diagrammatically at 22, may be either the conventional gas burners or electric heating units, depending on whether the range comprises a combination coal-wood-gas range or a coal-wood-electric range.

One of the end walls 23 has draft openings 24 in it. The rear wall is indicated at 25 in Figs. 3 and 5 and is provided with a rear flue 26.

A fire box 27 and conventional grates 28 are located in the upper left hand side of the range with an ash pan 29 beneath the same. The front wall 11 contains an opening 30 permitting withdrawal of said ash pan. The opening for the ash pan and the conventional type of fire box front with a wood fire door at the top is concealed normally by the left hand door 12. Said front wall also contains an equally large opening 31 giving access to a compartment which may be used for storage space or as a warming compartment or as a space in which to insert a water reservoir, as hereinafter described more fully. The door 13 normally conceals the opening 31.

Above the compartment referred to is a substantially horizontal flue casting 32 having reinforcing ribs 33. See Figs. 1, 4 and 5. This casting provides a flue between itself and the top of the range and constitutes an extension of the combustion chamber above the grates. A vertical partition 34, or cut-off casting, is arranged at the rear center of this upper space or combustion chamber, as shown in Fig. 1, and causes the heated air and gases from the fire box after they ascend therefrom, to travel toward the front of

- the stove before doubling back toward the rear flue, as shown by the arrows. Air enters the fire box through the long series of draft openings 24, which air circulates through and around the fire bed as indicated by the arrows in Fig. 1, the products of combustion serving to heat satisfactorily all four of the coal-wood lids and in particular the forward one of the two lids 20, which ordinarily would not receive much heat.
- 10 The products of combustion pass horizontally and rearwardly to the rear flue which contains a dividing wall 35 spaced from the rear oven wall 36, as shown in Fig. 5, thereby providing a flue 37. To the rear of this flue is a second flue 38 bounded by the walls 35 and 39 and having at the top a stove pipe flange 40 constituting the outlet. The products of combustion flow downwardly through flue 37 and upwardly through flue 38 and out through the stove pipe and chimney, as long as the damper 41 is closed as in Fig. 5. When the damper is open the gases entering the top of the rear flue rise directly into the stove pipe as indicated by the dotted lines in Fig. 1.
- 25 Attached to the back of the rear flue and spaced from the flue wall 39 there is provided a flue shield 42. This provides an auxiliary duct or flue 43 into which cold air enters at the bottom, absorbing heat as it rises, and issuing from the top thereof, it serves to heat the room. The shield 42 also serves to protect the room wall behind the stove from the heat. Sometimes protection is afforded in the form of a sheet of metal on the wall at the rear of the range. The flue shield 42 in the present case may be called a double duty shield in that it performs the double function of protecting the wall and increasing the efficiency of the rear flue as a circulating heater.
- 40 The center door 13, as previously stated, conceals a compartment which is separated from the combustion chamber by a vertical metal wall or partition 44 (see Fig. 1). The bottom of this compartment is provided with openings 45 through which cool air enters, which air is warmed and passes out through openings 46 in the rear of the stove, as shown in Fig. 3. This compartment is a very efficient warming oven, for dishes, utensils and other objects usually heated in this manner, being conveniently located and being supplied very effectively with heat from the fire box at the left, the horizontal flue casting immediately above, and the vertical rear flue.
- 55 Another important feature of construction is that the efficiency of the range as a room heater has been greatly increased over prior ranges of comparable type in that a much larger area has been provided for radiating heat from the 60 combustion chamber and cooking top. In fact, said area is substantially double that of the conventional kitchen heater, which latter usually radiates heat from one side only, i. e. the left side. In the improved construction disclosed herein with a compartment at the right of the fire box, heat is radiated both from the right and left of said fire box, and the provision of the ventilating holes referred to, makes the heat effective in warming the room. The rear flue in 70 prior constructions is usually just to the rear of the fire box whereas in the construction described herein said flue is to the right of the rear of the fire box and is in fact at the rear of the compartment referred to. As shown in 75 Figs. 1 and 3, this flue 26 does not completely

cover the rear wall of said compartment but leaves exposed a narrow vertical area or strip in which the vertical row of openings 46 are located. Thus the rear of the fire box section is not covered by and protected from radiation by 5 the flue. As a result heat is radiated freely into the room from the rear of said fire box. The flue casting 32 above the compartment referred to and underneath the two right hand coal lids 20, 20, provides extra area for the radiation of 10 heat downwardly into said compartment and thence into the room by circulation.

Furthermore, the back flue itself adds to the heating capacity and also constitutes a fuel saving feature. The fact that the heated air must 15 travel to the right beneath the coal cooking surface, before it enters the rear flue, insures a greater length of travel for said heated air whereby more of its heat is absorbed by the surrounding walls. Thus the heat loss through the 20 chimney is reduced.

As previously stated, the warming compartment may have a water reservoir or hot water tank in it. Such tank 50 is shown in Fig. 6 and a front view thereof is shown in Fig. 7. Water 25 is poured into the tank through the trough 51 near the top thereof and is drawn off through the swivel faucet 52 connected therewith at the bottom. The tank rests on a metal shelf 53 comprising part of a supporting base 54. The top of 30 the tank is covered with heat insulating material 55 and the two sides are also protected by coverings 56 of similar material, located in contact with the tank. An additional heat insulating panel 57 is provided below the tank leaving 35 a clearance space or dead air space between itself and the supporting shelf 53. Where the water tank insulation is part of a combination range in which electricity supplies the heating units in the right hand half of said range, an 40 additional electric heating unit 58 may be mounted in the dead air space referred to immediately below the metal support 53 and the tank. This auxiliary heater for the bottom of the reservoir may be a round electric heating unit similar to 45 those used on the cooking top of the range. With such an installation, a water temperature control device 59 is provided and also a water heater switch 60. Where the auxiliary electric heater is not desired, these auxiliary electrical devices are, 50 of course, omitted. In either case, where there is fuel burning on the grate, the water reservoir is heated through contact at the rear end thereof with the flue wall at the rear of the range, there being no insulation at the rear end of said reservoir. The fire box compartment immediately to 55 the left of the reservoir would supply considerable heat to an uninsulated reservoir and the horizontal flue casting above the same would also supply considerable heat, with the result that, under certain conditions, an excess of heat would be available. Therefore, the heat insulating covering just described is desirable and the reservoir heats very efficiently through its rear end contact and also holds its heat much longer 60 i. e. when the heat supply is reduced, than would otherwise be the case.

The water tank may be installed initially when the range is being assembled or it may be sold later as auxiliary equipment, to be installed by 70 the purchaser. In making the installation the reservoir is pushed back into contact with the rear wall of the range and held by any suitable device such as the small steel angle 61. A water tank equipped with an auxiliary electric heating 75

unit can also be installed by the purchaser of the range or preferably by an electrician.

The advantages of the combination range as a whole include the following:

- 5 The design is such as to provide four coal-wood cooking plates on the surface, whereas the conventional kitchen heater provides only two. Not only is a larger cooking top secured but a balanced arrangement of four cooking lids and four 10 gas burners or four electric burners. The rear flue is located at the rear to the right of the coal-wood section, thus bringing the stove pipe closer to the center of the range, this central location being emphasized by the splasher, mantle back, 15 and shelf, not shown herein. The front of the range is also balanced by virtue of the door arrangement previously referred to. The two coal-wood lids in the right hand row are amply heated due to the circuitous travel of the products of 20 combustion beneath the same. The efficiency of the range as a room heater has been greatly increased. The construction of the back flue insures additional heating capacity and economy of fuel. The rear wall or double duty shield also

provides an additional flue within which the ascending air is heated, further increasing the efficiency from this standpoint. The reservoir heats very efficiently and holds its heat much longer than the ordinary uninsulated reservoir. 5

I claim:

A range having a fire box chamber at one side, a compartment at the side of said fire box chamber, a substantially horizontal flue casting at the top of said compartment, a vertical down draft 10 flue against the outer surface of the rear wall of said range and covering the area immediately behind said compartment except for a narrow, vertical, uncovered portion thereof, said horizontal flue providing communication between said 15 fire box chamber and said vertical rear flue whereby said compartment is heated from the side, the top, and the rear, the bottom wall of said compartment having openings therein and said narrow, vertical portion also having openings 20 therein, whereby air may circulate through said compartment and serve to heat the surrounding outside air.

HERBERT T. BURROW.
